UNITED STATES PATENT OFFICE.

TEODORO GRUENWALD, OF GENOA, ITALY.

APPARATUS FOR THE CLEANING OF THE FLUES OF STEAM-BOILERS.

1,178,316.

Specification of Letters Patent.

Patented Apr. 4, 1916.

Application filed December 22, 1914. Serial No. 878,612.

To all whom it may concern:

Be it known that I, TEODORO GRUENWALD, a subject of the Emperor of Austria-Hungary, residing at Genoa, Italy, have invented certain new and useful Improvements in Apparatus for the Cleaning of the Flues of Steam-Boilers, of which the following is a specification.

This invention relates to apparatus for 10 cleaning flues of steam boilers and particularly to a modification of the apparatus described in my application Serial No. 868312 filed October 23rd, 1914. The present apparatus is more particularly useful in connection with boilers of the locomotive or like 15 type.

The invention is illustrated in the drawings.

Figure 1 is a longitudinal section through 20 a locomotive boiler supplied with the apparatus according to the present invention. Figs. 2 and 3 are details of the apparatus.

In these figures 6' is a rigid steam pipe which connects at one end by means of a 25 flexible tube 7 with a steam cock 5 upon the boiler or with the boiler dome and at the other end with the aspiration heads 4 (Fig. 2) situated in the fire box 11. Tube 6' is provided on one end with a handle 10 which 30 serves to turn said tube around its axis and on its other end with a guide-shaft 15, the latter serving to support the apparatus by its penetration inside one of the flues during 35 its turning movement or when being moved forward or backward. According to this form one, two or more aspiration heads 4 (Fig. 2) may be provided. In these heads the apertures 2 for the cleaning mixture may be arranged so that the cleaning mixture 40 leaves the heads in the same or in different directions. Each aspiration head has an inlet 3 for the hot gases and its external tube is provided with a connection for connecting the head with the tube 6'.

45 In order to apply the device to locomotive boilers, the fire door will be opened and the apparatus introduced into the fire box in such manner that the guide-shaft 15 will be supported inside one of the flues.

50 I claim:

1. Apparatus for cleaning the flues of steam boilers comprising a rigid pipe adapted to be introduced into the fire box of the boiler through the fire box door, a guide shaft arranged at the end of said pipe and adapted to rotatably engage within one of

the boiler flues, means for supplying steam to said pipe, an aspiration head laterally spaced from and mounted on said pipe and having an opening to draw in hot gases 60 from the fire box by the action of the steam, an outlet from said aspiration head directed toward the ends of the flues, and means for rotating said pipe whereby the said outlet is directed successively toward a series of 65 the flues.

2. Apparatus for cleaning the flues of steam boilers comprising a rigid pipe adapted to be introduced into the fire box of the boiler through the fire box door, a guide 70 shaft arranged at the end of said pipe and adapted to rotatably engage within one of the boiler flues, means for supplying steam to said pipe, a plurality of laterally spaced aspiration heads mounted on said pipe and 75 having an opening to draw in hot gases from the fire box by the action of the steam, an outlet from each of said aspiration heads directed toward the ends of the flues, and means for rotating said pipe whereby the 80 said outlets are directed successively toward a series of the flues.

3. Apparatus for cleaning the flues of steam boilers comprising a rigid pipe adapted to be introduced into the fire box of the 85 boiler through the fire box door, a guide shaft arranged at the end of said pipe and adapted to rotatably engage within one of the boiler flues, means for supplying steam to said pipe, an aspiration head laterally 90 spaced from and mounted on said pipe and having an opening to draw in hot gases from the fire box by the action of the steam, an outlet from said aspiration head directed toward the ends of the flues, and a handle on 95 said pipe external to the fire box for rotating said pipe whereby the said outlet is directed successively toward a series of the flues.

4. Apparatus for cleaning the flues of 100 steam boilers comprising a rigid pipe adapted to be introduced into the fire box of the boiler through the fire box door, a guide shaft at the inner end of said pipe in alignment with the same and adapted to engage 105 within one of the boiler flues, a flexible pipe external to the fire box for leading steam to the outer end of the rigid pipe, a plurality of aspiration heads arranged on, but laterally spaced from, said rigid pipe at the 110 inner end thereof and having openings to draw in hot gases from the fire box by the

action of the steam, an inclined outlet from each of said aspiration heads directed toward the ends of the flues, and a handle on said pipe external to the fire box for rotating said pipe whereby the said outlets are directed successively toward a series of the flues.

Copies of this patent may be obtained for five cents each, by addressing the "Commissioner of Patents, Washington, D. C."

In testimony whereof I have affixed my signature in presence of two witnesses.

TEODORO GRUENWALD.
